UNITED STATES PATENT OFFICE.

FREDERIC MYLIUS, OF ATLANTA, GEORGIA.

AEROPLANE.

1,074,007.

Specification of Letters Patent. Patented Sept. 23, 1913.

Application filed November 23, 1912. Serial No. 733,130.

To all whom it may concern:

Be it known that I, FREDERIC MYLIUS, a citizen of the United States, residing at Atlanta, in the county of Fulton and State of Georgia, have invented certain new and useful Improvements in Aeroplanes, of which the following is a specification.

This invention relates to certain new and useful improvements in aeroplanes and has for its primary object, the provision of novelly curved planes, which will support an aeroplane and give a forward impulse to the same when acted upon by suitable air pressure.

15 It is well known that to sustain an aeroplane the upward pressure of the air upon its planes must be equal in force to the weight of the machine. From this it will be readily appreciated that the shape and curvature of the planes upon which the air pressure is directed is of utmost importance and it is my aim to provide planes designed so as to secure the utmost lifting power with the minimum amount of air pressure.

25 In carrying out my invention, I provide a transverse plane, which will be termed a carrier plane, having a concave upper surface, and guide planes secured at their edges adjacent the forward ends thereof, to the transverse plane, said guide planes converging rearwardly and being connected to each other at their rear extremities. These guide planes are doubly curved, having their upper surfaces adjacent their forward ends concave, and adjacent their rear ends convex. This structure insures a steady pressure of air upon the under surfaces of the planes, in such a manner as to impart to the forward ends thereof, a lifting force.

30 The invention also aims to provide suitable means whereby the machine may be easily controlled.

With these and other objects in view as will become more apparent as the description proceeds, the invention consists in certain novel features of combination, construction, and arrangement of parts, which will be hereinafter fully described and claimed.

For a complete understanding of the invention, reference is to be had to the following description and accompanying drawings, in which—

Figure 1 is a top plan view of my aeroplane. Fig. 2 is a side elevation. Fig. 3 is a front elevation. Fig. 4 is a vertical sectional view through the forward part of the machine, showing the engine and parts connected therewith, in elevation. Fig. 5 is a detail perspective view of a portion of one of the rudders and its connections. Fig. 6 is a detail view illustrating the method of connecting one of the operating levers adjacent the side of the operator, and, Fig. 7 is a detail view of a part to be hereinafter described.

Referring in detail to the drawings by numerals, 1 designates rearwardly converging side bars and 2 a curved bar connecting the forward ends of the bars 1, thereby forming an inner frame, which appears segmental in plan.

3 designates rearwardly converging side bars of an outer frame, said side bars being connected by means of the straight transverse bars 4, to a downwardly and forwardly curved bar 5. Bars 6 positioned in longitudinal alignment with the bars 1, connect the inner frame at its forward end to the outer frame and the longitudinal frame bar 7 connects the rear ends of the inner and outer frames. As shown in Fig. 1, the corresponding bars of the frames are parallel and give to the structure a somewhat triangular shape.

Upon reference to Fig. 2, it will be seen that the frame bars 1 are straight, whereas the bars 3 are doubly curved, each having its upper surface concave for the forward half of its length, as at 8, and convex for the other half, as at 9. In other words each of the side bars extends downwardly from its forward end, then upwardly and again downwardly, forming a double curve. The bars 4 to which the forward ends of the guide planes 10 are secured, are essentially straight and inclined slightly upwardly

from their inner ends. The frame bars 2 and 5 extend downwardly and forwardly from their extremities in regular curves and have secured between them, the carrier plane 11. The ends of this plane are attached to the frame bars 6. The guide planes 10 are attached, as is clearly shown in Fig. 1, to the frame bars 1, 3 and 7, said last mentioned bar being essentially straight and inclined downwardly and rearwardly. It will be apparent that an upward air pressure on the carrier plane 11, will tend to support the aeroplane and the same pressure acting upon the guide planes 10 will give to the machine a forward motion. The manner in which the guide planes converge rearwardly also increases the tendency of the machine to a forward motion when acted upon by a lifting air pressure.

20 A car frame is supported by the frame bars 2 and 5. The car frame comprises top parallel bars 12, front downwardly converging bars 13, an angular centrally positioned bottom bar 14, and rearwardly converging end bars 15. The top bars 12 are connected to the frame bars 2 and 5, by means of suitable straps 16 and the various bars forming the car frame are connected by couplings, as clearly shown in Fig. 4. If desired, preferably canvas strips 17 may be employed to form the walls of the car. An engine 18 is suitably secured within the car and drives the shaft 19 to which is secured the fly-wheel 20 and pulleys 21. Belts 22 are employed 35 to drive the propeller shafts 23, through the medium of the pulleys 24, which are rigidly secured upon said shafts. The shafts 23 are secured to the bars 12, by means of the hangers 25, said hangers being formed upon 40 sleeve members 26, which are secured in position by set screws 27. The aeroplane may be guided and vertically supported by the rudders 28 and 29, which comprise preferably canvas strips secured within suitable frames. A central rod 30 extends longitudinally of each of the rudders through a suitable bearing 32. Steering rods 33 are connected to the cranks 32 and to suitable levers 34. These levers are positioned adjacent a seat 35 and are pivotally connected at their lower ends to a bar 36, said bar being provided with two pairs of spaced ears 37. It will be seen that this construction permits the operator to readily shift the 55 rudders either simultaneously or individually, so as to direct the machine as desired. Supporting wheels 38 are journaled within the lower ends of standards 39.

It is to be understood that I do not wish 60 to be confined to the exact curvature of the side planes herein described, but may change them as well as the carrier plane, provided the changes fall within the spirit and scope of the invention.

The car frame and main frames may also 65 be greatly varied in their structure without departing from the spirit of the invention.

Having thus described my invention, what I claim is:—

1. An aeroplane comprising a transverse 70 carrier plane having its upper surface concave, and rearwardly converging guide planes secured at their forward ends to the carrier plane, said guide planes having their upper surfaces concave adjacent their forward ends and convex adjacent their rear ends.

2. An aeroplane including a carrier plane extending downwardly and forwardly, and rearwardly converging guide plates 80 secured at their inner edges adjacent their forward ends to said carrier plane, the outer edge of each guide plane being doubly curved, having its forward half concave and its rear half convex, the inner edges of said 85 guide planes being essentially straight.

3. An aeroplane comprising an outer frame, an inner frame, planes secured between said frames, the outer frame having rearwardly converging doubly curved side 90 bars and a downwardly and forwardly curved front bar, the inner frame having straight rearwardly converging side bars and a downwardly and forwardly curved front bar, and means for connecting said 95 frames.

4. An aeroplane comprising an outer frame somewhat triangular in plan, an inner frame spaced from said outer frame and segmental in plan, means connecting said frames, a downwardly and forwardly curved carrier plane secured between the forward ends of said frames, doubly curved guide planes secured between the sides of said frames, said guide planes having their upper surfaces concave adjacent their forward and convex adjacent their rear ends, a car supported by said frames, means for propelling the aeroplane, and means for steering the same.

5. An aeroplane comprising an outer frame having rearwardly converging doubly curved side bars and a downwardly and forwardly curved front bar, an inner frame having rearwardly converging side bars and a forwardly and downwardly curved front bar, planes secured between said frames, a car frame-work supported by the forward bars of said first mentioned frames, an engine mounted in the car frame-work, propeller shafts driven by said engine, a pair of rudders secured adjacent the rear end of the outer frame, means for actuating said rudders, and an operator's seat positioned adjacent the forward ends of said last mentioned means.

6. A device which moves through a sustaining medium and which is supported

therein by means of planes, one of said planes constituting a carrier plane extending transversely of the forward end of the device, the remaining planes constituting 5 guide planes and converging rearwardly from the extremities of said carrier plane, the guide planes being concavo-convex and having their upper surfaces concave adja-

cent their forward ends and convex adjacent their rear ends.

In testimony whereof I affix my signature in presence of two witnesses.

FREDERIC MYLIUS.
